Specification for Design.

Patented Feb. 10, 1920.

Application filed July 12, 1919. Serial No. 310,490. Term of patent 3½ years.

To all whom it may concern:

Be it known that we, EDMUND SCHULTE, a citizen of the United States, residing in Yonkers, county of Westchester, and State of New York, and JOSEPH WEITE, Jr., a citizen of the United States, residing in Yonkers, county of Westchester, and State of New York, have invented a new, original, and ornamental Design for a Candelabrum, Cigar, Cigarette, and Match Holder and Ash-Receiver, of which the following is a specification, reference being had to the accompanying drawing, forming a part thereof.

In the drawings:—

Fig. 2 is a plan view and

Fig. 3 is a side elevational view.

We claim:—

The ornamental design for a candelabrum, cigar, cigarette, and match holder and ash receiver as shown.

EDMUND SCHULTE.
